UNITED STATES PATENT OFFICE.

OLE P. OVERLIEN, OF BLACK RIVER FALLS, WISCONSIN.

DOUBLE-DOOR-ACTUATING DEVICE.

1,373,567.

Specification of Letters Patent.

Patented Apr. 5, 1921.

Application filed March 6, 1920. Serial No. 363,875.

To all whom it may concern:

Be it known that I, OLE P. OVERLIEN, a citizen of the United States, and resident of Black River Falls, in the county of Jackson 5 and State of Wisconsin, have invented certain new and useful Improvements in Double-Door-Actuating Devices; and I do hereby declare that the following is a full, clear, and exact description thereof.

10 My invention refers to semi-automatic controlling mechanism for companion swinging doors, its primary object being to provide a simple, effective and durable mechanism of the above character which can be 15 readily attached to garage doors or the like and which will act under spring or weight control to close the doors tightly after an initial manual movement in one direction and to hold them securely open after an initial 20 manual movement in the other direction, thus avoiding the tendency of the doors to swing open or close whereby some means would have to be employed to hold them in their different positions.

25 Specific objects of my invention are:

To provide means for adjusting the apparatus whereby it can be attached to doors of different dimensions.

30 To provide means for adjusting the mechanism whereby the doors are held open at predetermined angles with respect to the door opening.

35 To provide means in connection with the apparatus whereby the spring or weight mechanism can be attached to either the right or left hand door.

40 With the above and other objects in view the invention consists in certain peculiarities of construction, combination and arrangement of parts as are hereinafter set forth with reference to the accompanying illustrations and subsequently claimed.

In the accompanying drawings:

45 Figure 1 represents a plane sectional view through a door opening provided with hinged doors equipped with a controlling mechanism embodying the features of my invention, the doors being shown in their open position.

50 Fig. 2 is a similar view showing the doors in their closed position.

Fig. 3 is a detail cross section through one of the bracket members, the section being indicated by the line 3—3 of Fig. 1.

55 Referring by numerals to the drawings, 1, 1 represents the door casing of a building

provided with doors 2, 3 which are connected to the casing by hinges 4, 4 in the ordinary manner. For clearness in the description the door 2 may be termed a master door 60 while the door 3 may be termed a trailer door.

The master door 2 has fitted thereto when its upper end is in close proximity to the hinges, a bracket 5, which bracket is provided with a series of apertures 6 for selective engagement with the down turned end of a rod 7, the same being in hinge connection with the aperture. The rod 7 is in telescopic union with a hollow rod 8 being held 70 against telescopic movement by a set screw 9 with which the hollow rod 8 is provided.

The opposite end of the rod 8 has secured thereto a pintle head 10, which pintle head has a shank 10' that is hingedly mounted in 75 an aperture of a bracket 11. The bracket 11 is secured to the trailer door 3 being positioned with relation to the door corresponding to the bracket 5 which is carried by the master door. The bracket 11 is provided 80 with two or more apertures 12 for a bolt 13 which bolt passes through a slot 14 that is formed in a stop-arm 15, the same being provided with an up turned end, as best shown in Fig. 3, in engagement with the protruding 85 terminal of the rod 8 whereby movement of this rod upon its pivot is limited. The stop-arm is thus rendered adjustable with relation to the end of the rod 8 so as to regulate the scope of the angular position that the 90 door may assume when in a full open position. The bracket 11 is provided with a plurality of apertures 12 for the purpose of reversing the position of the stop-arm when it is desired to place this mechanism upon the 95 opposite door from that shown, in which case the master door mechanism would also be reversed as to its position with the pair of doors.

The bracket 5 is provided with a series of 100 apertures 6 for the purpose of adjusting the downturned end of the rod 7 at different distances from the hinge point of the door whereby variation in the throw of the door is also effected.

105 The bracket 5 is provided with an inwardly extending arm 16 for the reception of one end of a spring 17 the opposite end of said spring being anchored to the door frame by an ear 17', it being understood, 110 however, that this anchor may be located upon the ceiling of the building or in any

other convenient position so as to effect the desired spring control whereby the master door will be closed by the spring when said door is swung initially inwardly to a pre-
5 determined point from the position shown in Fig. 1.

While I have shown a spring for accomplishing these results obviously I may substitute the equivalent element a weight, in
10 which instance a cord or other runner would be attached to the arm 16 and the same would be trained over suitable pulleys with the weight at its free end in such manner that gravity would function to ac-
15 complish the closing action.

From the foregoing description and by referring to Fig. 2 of the drawings it will be seen that should manual power be applied to the handle α of the master door in
20 the direction as indicated by the arrow the door will be swung outwardly to approximately the position shown in dotted lines in Fig. 1 of the drawings. This action is effected in opposition to the spring.

25 When the master door assumes the dotted line position as in Fig. 1 the composite rods 7 and 8 constituting a "link" will cause an outward pull upon the trailer door 3 whereby said door will swing upon its hinges to
30 the position indicated in dotted lines in Fig. 1.

In this position the link connecting the doors will assume a dead center position with relation to the hinge axis of the trailer
35 door and the pintle head 10.

With the parts in this position the operator will now exert a slight manual force upon the door 3 in an outward direction so as to cause the pintle to pass the imaginary
40 dead center position and simultaneously with this movement the spring 17 will exert its force to cause a slight retraction of the door 2 from its dotted line position to its full line position as shown in Fig. 1. In
45 describing this slight backward movement of the master door under spring tension the trailer door will be, through its link connection, forced from its dotted line position to its full line position as shown in Fig.
50 1. Thus the spring will now hold both doors assuming a position slightly over ninety degrees from their point of closure.

If it should be desired to adjust the doors so that they will swing through approximately ninety degrees for example the rod 7 can be placed in the bracket aperture nearer the hinge point of the master door whereby the combined throw or outward swing of the door will be limited. This function of adjustment is desirable where a garage may have a second set of doors having a very narrow space between them and the first set in which case unless the doors were accurately adjusted as to outward swing they might come in contact with each other to prevent proper functioning.

While I have shown and described one exemplification of my invention in all of its details it is manifest that I may vary such details of construction without departing from the spirit of the invention as called for in the claims.

I claim:

1. The combination of oppositely swing-
ing hinged doors, brackets for the doors se-
cured to the same near their hinges, a clos-
ing spring for one door, a link having a
pivotal connection to the bracket of said
door and also to the bracket of the other,
the link being of such length that the latter
pivotal connection crosses the dead center
line passing through the adjacent hinge and
the other pivotal connection when the doors
are opened or closed. 75

2. The combination of oppositely swing-
ing hinged doors, brackets for the doors se-
cured to the same side near their hinges, a
closing spring for one door, a link having a
pivotal connection to the brackets of said
door and also to the bracket of the other,
the link being of such length that the latter
pivotal connection crosses the dead center
line passing through the adjacent hinge and
the other pivotal connection when the doors
are opened or closed, and a stop carried by
one of the door brackets engageable with
the link for limiting outward swing of said
doors. 80 90 95

In testimony that I claim the foregoing I have hereunto set my hand at Milwaukee, 100
in the county of Milwaukee and State of Wisconsin.

OLE P. OVERLIEN.
